TOY DOG

Jose Jesus Cardenas Chavez, 4780 Imperial Ave.,
San Diego, Calif. 92113

Filed June 29, 1972, Ser. No. 267,365

Term of patent 7 years

Int. Cl. D21—01

U.S. Cl. D34—2 R

FIG. 1.

FIG. 2.

FIG. 1 is a perspective view of a toy dog showing my new design, the side opposite being substantially similar to that shown.

FIG. 2 is a typical section through one of the body and leg sections.

I claim:

The ornamental design for a toy dog, as shown and described.
